Patented Dec. 5, 1916.

FIG. 1.

Burton P. Hall
Inventor
By his Attorney
Israel Benjamins.

UNITED STATES PATENT OFFICE.

BURTON P. HALL, OF FANWOOD, NEW JERSEY.

FIRE-EXTINGUISHER.

1,207,398.

Specification of Letters Patent.

Patented Dec. 5, 1916.

Application filed May 20, 1916. Serial No. 98,920.

To all whom it may concern:

Be it known that I, BURTON P. HALL, a citizen of the United States, residing at Fanwood, in the county of Union and State 5 of New Jersey, have invented a new and useful Fire-Extinguisher, of which the following is a specification.

My invention relates to improvements in fire extinguishers, and it consists in the 10 novel features hereinafter more fully described.

The objects of my improvement are: First: To produce a fire extinguisher of great efficiency. Second: To produce a fire 15 extinguisher in which two or more chemical reagents are brought into contact with each other by the application of a small force from the outside of the container inclosing said reagents, thereby producing a gaseous 20 pressure on the extinguishing fluid in the tank of the fire extinguisher. Third: To provide a means for instantly sealing the tank of the fire extinguisher when gas is produced, thereby effectively preventing the 25 leakage of the gas and the reduction of pressure due to said leakage, and to avoid the use of stuffing boxes, bushings and similar expedients. Fourth: To have said fire extinguisher and said tank sealing device simple, durable, inexpensive and adapted to be 30 operated by unskilled persons. I attain these objects by the apparatus illustrated in the accompanying drawings or by any mechanical equivalent or obvious modification 35 of the same.

In the drawings the figure is a vertical section of one form of my extinguisher.

11 is the outer container or tank, adapted to contain the fire extinguishing liquid under pressure of a gas. 12 is the cap or cover adapted to detachably close the said outer container or tank 11. 12^a is a hub made in one with said cap 12 on the underside thereof; it has formed therein the central tapered opening 25, hereinafter more fully described; and it is shown as connected to the perforated socket 16 by means of a suitable screw thread on its outer periphery. Said socket 16 is shown as having a 40 horizontal shoulder at its lower end. 16^a are the apertures or openings in said socket 16, which apertures are normally covered by tinfoil 16^b, of which the thickness is shown as exaggerated for the sake of clearness. 12^b is a boss on the upper side of said cap 12; it encompasses the upper end of

said tapered opening 25 and serves as a seat for the spring 28 and knob 27, hereinafter described. 13 is a suitable gasket or packing adapted to seal the mouth of said container or tank 11 gas tight, when the latter is closed by said cap or cover 12. 14 is a vessel or cartridge suspended inside of said container 11 by means of the gland 15, which is shown as resting on the horizontal shoulder of said socket 16. Said cartridge 14 is shown as inclosing one of the reagents 29, such as bicarbonate of soda, for producing the gaseous pressure; the other reagent, such as sulfuric acid, is contained in 70 the bottle 17, which is shown as resting on the pointed end of a screw 19, carried by the bottom 24^b of the open cage 24, which is shown as connected at its upper end to the lower edge of said socket 16, inside of said 75 cartridge 14. 24^a are the openings in said cage 24. 18 is a washer, which is shown as resting on the upper edge of said bottle 17, which is shown in elevation, and on the stopper 17^a, which is shown as having its 80 upper end flush with the upper edge of said bottle 17, thereby closing the same. 22 is an eduction tube or conduit for the extinguishing fluid; 20 is a nozzle at the upper end of said tube 22; 21 is a bend 85 connecting said nozzle 20 to said tube 22, and shown as formed in one therewith, but a separate elbow may be employed, if desired. 23 is a strainer at the lower end of said tube 22. 25 is a tapered opening 90 formed in the central part of said cap 12, its hub 12^a and boss 12^b; it is adapted to fit the tapered push rod 26, and the inclination of the taper of said opening 25 and said push rod 26 is such as to cause the said push 95 rod 26, when driven home into said opening 25, to remain in position in said opening 25 against a considerable endwise pressure from within said container 11, thereby sealing the joint formed therebetween. 27 is a knob at the upper end of said push rod 26 for applying the hand thereto, whereby said push rod 26 may be driven into said opening 25. 28 is a compression spring 100 shown as connected at its upper end to said push rod 26 and at its lower end to said boss 12^b; it tends to keep said push rod 26 normally off said opening 25. The lengths of said push rod 26 and of said opening 25 are such, that, when said push rod 26 is 105 driven home, its lower end will extend beyond the lower end of said opening 25, and

it will strike the washer 18, thereby producing a pressure on said bottle 17 lengthwise thereof, which pressure will be concentrated at the lower end of said bottle 17. 5 where it rests on the pointed end of the screw 19; this will cause the bottle to break at its lower end, liberating its contents, which will flow out through the openings 24^a of said cage 24, and will thereby be 10 brought into contact with the reagent 29, causing the evolution of a gas, which will pass through said openings 24^a into said cage 24, thence into said socket 16, whence the gas will pass, by rupturing the tinfoil cover 16^b of the apertures 16^a, into the container or tank 11, causing the extinguishing fluid to escape through the strainer 23, tube 22 and nozzle 20.

It is evident that said screw 19 with the 20 lower end of said push rod 26 form an effective means for bringing the chemicals inclosed by said vessel 14 into contact with each other and that a single light blow with the palm of the hand on said knob 27 will 25 cause the reagents in the vessel 14 to be brought into contact with each other, and it will also instantly seal the tank 11 to prevent the leakage of the gas under pressure.

30 No stuffing boxes, bushings or any similar expedients are employed.

It is evident that my fire extinguisher may be modified a great deal within the scope of my invention.

35 I do not, therefore, restrict myself to the details of my fire extinguisher as shown in the drawings; but I intend to include also all mechanical equivalents and reasonably obvious modifications of the same.

40 What I claim as my invention and desire to secure by Letters Patent, is:

1. A fire extinguisher comprising a tank adapted to contain a fire extinguishing liquid under pressure of a gas, a means for 45 keeping two or more chemicals out of contact with each other inclosed by said tank, a tapered seat on said tank, a tapered member adapted to fit said seat, the taper of said member and said seat being so small as to 50 cause said member to remain in position when brought home to said seat, against the pressure of said gas, said tapered member being normally off said seat and adapted to be moved toward said seat, and means for 55 coöperating with said member to bring said chemicals into contact with each other by the motion of said member toward said seat, thereby producing said gas.

2. A fire extinguisher comprising a tank 60 adapted to contain a fire extinguishing liquid under pressure of a gas, a means for keeping two or more chemicals out of contact with each other inclosed by said tank, a tapered opening in said tank, a tapered 65 push rod adapted to fit said opening, the

taper of said push rod and said opening being so small as to cause said push rod to remain in position, when driven home into said opening, against the pressure of said gas, said push rod being normally off said opening and adapted to be moved into it, and means for coöperating with said push rod to bring said chemicals into contact with each other by the motion of said push rod into said opening, thereby producing said 75 gas.

3. In a fire extinguisher a tank, adapted to contain a fire extinguishing liquid under pressure of a gas, a means for keeping two or more chemicals out of contact with each other inclosed by said tank, a tapered seat on said tank, a member having a tapered surface adapted to fit said seat, the taper of said surface and said seat being so small as to cause said member to remain in position, when brought home to said seat, against the pressure of said gas, said member being normally off said seat and adapted to be moved toward said seat, a means for coöperating with said member to bring said chemicals into contact with each other by the motion of said member toward said seat, thereby producing said gas, and a spring adapted to keep said member normally off said seat and to allow the moving of said 95 member toward said seat.

4. In a fire extinguisher the combination of a tank adapted to contain a fire extinguishing liquid under pressure of a gas, a receptacle, adapted to contain one or more 100 chemicals, inclosed by said tank, a bottle, adapted to contain a suitable reagent, inclosed by said receptacle, said receptacle having one or more orifices, adapted to communicate with the inside of said tank, 105 a suitable covering for said orifice or orifices, adapted to prevent the ingress of said liquid into said receptacle, said covering being adapted to be ruptured by the pressure of said gas, a tapered opening in said tank, a member having a tapered surface, adapted to fit said opening, the taper of said surface and said opening being so small as to cause said member to remain in position when brought home into said opening, against the 110 pressure of said gas, said member being normally off said opening and adapted to be moved into it, and means for coöperating with said member to bring said reagent into contact with said chemical or chemicals by 115 the motion of said member into said opening, thereby producing said gas.

5. In a fire extinguisher a tank adapted to contain a fire extinguishing liquid under 120 pressure of a gas, a means for containing a chemical inclosed by said tank, a suitable bottle inclosed by said means, said bottle being adapted to contain a chemical reagent, thereby separating it from said first named chemical, a suitable cage for supporting said 125

- bottle in position, a screw passing through the bottom of said cage and abutting against the lower end of said bottle, a washer placed against the upper end of said bottle, a tapered opening in said tank opposite said washer, a tapered member adapted to fit said opening, the taper of said member and said opening being small, thereby causing said member to remain in position, when brought home into said opening, against the pressure of said gas, said member being normally off said opening and adapted to be moved into it, and to strike said washer when moved into said opening, thereby causing the lower end of said bottle to be broken, thereby bringing said reagent into contact with said chemical or chemicals, and thereby producing said gas.
6. In a fire extinguisher a tank adapted to contain a fire extinguishing liquid under pressure of a gas, a means for keeping two or more chemicals out of contact with each other inclosed by said tank, a tapered seat on said tank, a member having a tapered surface adapted to fit said seat, the taper of said surface and said seat being so small as to cause said member to remain in position, when brought home to said seat, against the pressure of said gas, said member being normally off said seat and adapted to be moved toward said seat, means for coöperating with said member to bring said chemicals into contact with each other by the motion of said member toward said seat, thereby producing said gas, and a means for keeping said member normally off said seat and to allow the moving of said member toward said seat.
7. In a fire extinguisher the combination of a tank, a cap on said tank, a hub on the underside of said cap, a perforated socket connected to said hub, a cartridge or shell, adapted to contain a chemical or chemicals, suspended from said socket, a cage connected to said socket inside of said cartridge, a screw passing through the bottom of said cage, a bottle adapted to contain another chemical supported on the end of said screw, a tapered opening in said cap and hub, a tapered push rod adapted to fit said opening, and to break said bottle, thereby bringing said chemicals together and thereby producing said gas, the taper of said opening and of said push rod being small, thereby causing the sealing of the joint between them when said push rod is driven home, and a suitable covering for the apertures of said socket, said covering being adapted to be ruptured by the pressure of said gas.

BURTON P. HALL.
